H. Mall Pettit.

UNITED STATES PATENT OFFICE.

FREDERICK G. WARRELL, OF PHILADELPHIA, PENNSYLVANIA.

TELEPHONE ANNUNCIATOR AND CALL-BELL.

SPECIFICATION forming part of Letters Patent No. 524,009, dated August 7, 1894.

Application filed June 25, 1891. Serial No. 397,456. (No model.)

To all whom it may concern:

Be it known that I, FREDERICK G. WARRELL, of the city of Philadelphia and State of Pennsylvania, have invented a certain new and useful Improvement in Telephone Annunciators and Call-Bells; and I do hereby declare the following to be a full, clear, and exact description thereof, reference being had to the accompanying drawings, forming part of this specification.

My invention has relation to telephone annunciators and call-bells and consists in the combination and system hereinafter described.

15 The object of my invention is to provide a combined system of telephone and call-bell annunciators for hotel, house and other such like purposes of simple and inexpensive construction so that the call indicated by the annunciator may be connected by telephone communication by the mere adjustment of the proper switch at the switch board; and in which each of the respective terminals may be connected with the annunciator and central telephone on independent circuits.

The accompanying drawings illustrate my invention.

Similar letters and figures of reference refer to similar parts throughout.

30 Figure 1 illustrates my invention, showing, however, only one call-bell and telephone of the system connected with the annunciator. Fig. 2 is an enlarged sectional view of the telephone and push button on the line $a-x$ of Fig. 1. Fig. 3 is a side elevation of the annunciator, switch board and telephone attached thereto.

E represents an annunciator of ordinary construction connected by wires, a b' , connecting with the push buttons, B, at the terminals; a battery, B', is also provided at any desired point.

A represents a telephone, which in the form illustrated in the drawings serves as both receiver and transmitter as does also the telephone A', at the annunciator end of the line; independent receivers and transmitters can be applied when desired at either or both ends; the transmitter and receiver, A, is provided at each terminal with the push button,

B, and connected with the annunciator call-bell system of wiring, say with the wire, a , by the auxiliary wire, a' .

A switch board, S, is provided to the annunciator, E, having a switch, p , for each terminal or indicator of the annunciator, each switch being electrically connected, as by the wire, a^2 , with its main wire to its respective terminal, as with the main wire, a ; the receiver and transmitter A', is adjustably connected by a plug or switch with each switch of the board S.

Any form of switch or key and switch board device may be employed; in the drawings I have illustrated a simple form of flexible covered wire, w , connected at one end with the receiver and transmitter, A', and at the other end provided with a plug, p' , illustrated as disconnected in Fig. 1, but adapted to be engaged in the switch orifices, p , of the switch board, S, when it is desired to place the telephone in circuit, as shown in Fig. 3, or it may be connected by any switch device, as above stated. Each terminal desired to be connected is provided with a telephone, call-bell and wiring connections similar to the single connection as illustrated in the drawings.

Referring to the drawings, when the push button, B, is pressed the arrow on the annunciator will indicate say room, No. 27; the plug, p' , provided on the end of the flexible wire, w , will then be inserted in the orifice 27 of the switch board by the person in charge at the annunciator, and thus telephonic connection will be had directly between the telephone, A', through the medium of the wire, a , with the telephone, A; the bell circuit being broken at the push button, B; when it is desired to disconnect the telephone the switch plug, p' , is removed to a hook, or other temporary position, as shown in Fig. 1, ready to be inserted in any other switch of the switch-board which the annunciator may indicate. The telephone is preferably grounded by the wire, a^3 at one end and by the wire, a^4 at the other end.

It will be noted that in my invention each room or terminal is connected independently and directly with the central telephone and annunciator by a separate independent cir-

cuit, allowing the annunciator to operate and indicate whenever the button is pressed at any terminal, notwithstanding another terminal may be in circuit, and will thus enable 5 the operator to immediately connect with that terminal when disengaged at the phone circuit on the other.

I have described the construction of an- 10 nunciator and telephone as connected on the same system of wiring, but separate systems of wiring for the telephone and call-bell an- 15 nunciator may be employed, if desired, connected and constructed at the annunciator terminals as described. Buildings already 15 provided with annunciators and call-bell sys- tem of wiring can readily be fitted with my invention on the same system of annunciator wiring.

I do not limit myself to the particular con- 20 struction described and shown, as my invention may be employed in numerous construc- tions. The electric generator or battery, B', connected with the call-bell system may be 25 directly connected with the wire, a, if desired, and the wire, b', also grounded, if preferred; numerous constructions of switches, as before stated, may be also employed.

I have described a battery provided to the call-bell, this is a preferable construction, but 30 I do not limit myself to the use of a battery; frictional and other annunciators may be em- 35 ployed in carrying out my invention.

I am aware that combined telephone and 35 annunciator systems of communication have heretofore been invented in which the re- 40 spective telephone and call-bell terminals by a complicated system of circuit wiring and switches are operated on the same circuit and all rooms connected on one main circuit with the central telephone and annunciator through branches leading from the main cir- 45 cuit. The combined system of telephone an- nunciators I do not claim broadly; my inven-

tion consists in the device and system herein particularly described and claimed. 45

Having thus described my invention, what I claim, and desire to secure by Letters Patent, is—

1. The combination in an electric annunciator and telephone system of a central an- 50 nunciator, E, provided with electrically op- erated indicating hands each hand connected with one of the terminals of the system, a central telephone receiver and transmitter, a central switch board connecting said cen- 55 tral telephone by means of a switch or plug with each of the respective telephone terminals, a telephone and push button provided at each terminal of the series, said push but- 60 ton adapted to make or break at will the tele- phone and signaling circuits, independent circuits connecting each terminal with the annunciator and central telephone, a metallic signaling circuit being part of the talking cir- 65 cuit, ground connections provided at each tele- phone terminal substantially as described.

2. An annunciator, E, call bell, b, wiring connections, a, b', ground wires, a³, a⁴, bat- 70 ttery, B', push button, B, telephones, A, con- nected directly at each terminal with the call- 75 bell system of wiring, central telephone, A', provided at the annunciator, switch, board, S, and switch connections connecting the cen- tral telephone, A', with the switch board, S, each telephone and push-button of the series 80 of telephone terminals and push buttons be- ing connected by circuits with the annunciator and central telephone independent of each of the other respective terminals sub- stantially as described.

In witness whereof I have hereunto set my hand this 22d day of June, A. D. 1891.

FREDERICK G. WARRELL.
